UNITED STATES PATENT OFFICE.

BRUCE V. EDWARDS, OF NEWARK, NEW JERSEY, ASSIGNOR, BY MESNE ASSIGNMENTS,
TO THE BURCHELL-JOHNSTON CORPORATION, A CORPORATION OF NEW YORK.

THERMOSTATIC APPARATUS.

1,211,117.

Specification of Letters Patent.

Patented Jan. 2, 1917.

Application filed March 28, 1914. Serial No. 827,826.

To all whom it may concern:

Be it known that I, BRUCE V. EDWARDS, a citizen of the United States, residing at Newark, in the county of Essex and State 5 of New Jersey, have invented certain new and useful Improvements in Thermostatic Apparatus, of which the following is a specification, reference being had therein to the accompanying drawing.

10 This invention relates to thermostatic apparatus operating to control an electric circuit for sounding an alarm, operating sprinkler systems, or performing other functions, and the invention has special reference to 15 that type of apparatus in which the volumetric changes of a fluid body, such as are due to temperature changes, will operate to control the circuit.

The object of the invention is to produce 20 a device of this character designed more particularly for use in rooms, halls, warehouses and like situations, for indicating the presence of a fire or conflagration, which device will be compact in form, and simple 25 in construction; and which device while under gradual temperature changes, such as climatic changes and those ordinarily occurring in such locations, will not operate to perform its functions, yet will be very sensitive 30 to action under sudden temperature changes, and in such conditions will operate with promptness and certainty in effecting the circuit control.

With these objects in view, my invention 35 consists in combining with a body or casing containing a fluid expansion chamber, a liquid column contained within and surrounded by said chamber, so that the column will be raised by the expansive action 40 of the fluid in the chamber, and suitable means operated by the rise of the liquid column, to control an electric circuit.

The invention consists also in the details 45 of construction and combination of the parts hereinafter described and claimed.

In the accompanying drawings: Figure 1 is a vertical sectional elevation through my improved device as it appears attached to the ceiling of a room. Fig. 1^a is a fragmentary view of the apparatus shown in Fig. 1, showing the action of the parts in closing

the circuit. Fig. 2 is a sectional elevation of a modified form of the apparatus.

Referring to the drawings: 1 represents a fluid expansion chamber inclosed by a 55 wall, consisting of the hemispherical metal casing 2, and the circular plate 3 fitting within the casing near its edge, and sealed fluid-tight therein. The chamber is adapted to contain air, which is the expansive 60 fluid employed in the present instance, and the thickness of the casing 2 is such that while it will possess the necessary rigidity, it will permit the contained air body to be 65 promptly influenced by the external temperature changes.

Extending into and surrounded by the chamber, is an upright tube 4 open at both ends, the upper end of which is fixedly secured in an opening in the center of the 70 plate 3, while its lower end terminates a short distance above the bottom of the casing 2, which latter is depressed or deepened at its center so as to form a well 2^a. Within the casing is placed a quantity of liquid 5, 75 preferably glycerin or oil, in volume sufficient to fill the well 2^a and to spread out in the bottom of the casing, so as to present its upper surface to the expansive action of the air in said chamber. As a result of this 80 construction and arrangement of the parts, an increase of temperature of the air outside the casing, will heat the air body in chamber 1, and the pressure on the surface of the liquid will force the same up into the 85 tube, in the form of a column 5. I propose to utilize the rise of the column, 5, to control an electric circuit, in the present case to close a normally open circuit. This is effected in the form of apparatus shown, by 90 means of a contact body in the form of a float 7 of conductive material, which is supported on the upper end of the column 5. This float when raised by the column, is adapted to contact with the inner ends of 95 two electric circuit terminals 8 and 9 connected with but insulated from the plate 3, and having their inner extremities in position to be engaged by the float as described, by which action the circuit will be closed. 100 through the said terminals, which are electrically connected to the conductors 8^a and

9^a of the circuit. The above described operations are adapted to take place only in the event of a sudden rise in temperature outside of the casing 2, such as would occur from a fire or conflagration, and in order to insure this action and prevent the column from being raised by gradual temperature changes such as ordinarily occur from climatic changes and from the ordinary heating of the room, I provide a vent opening 10 in the wall of the chamber 1, in the present instance this opening being formed in the plate 3. This opening is of such size that while it will permit the air to escape when the expansion of the air body is slow and gradual, and in this way will prevent a sufficient increase in volume to raise the liquid column, yet it will not prevent sufficient air to escape when the expansion in the chamber 1 is rapid or sudden, to check such increase in volume of the air as to elevate the column. Therefore it is only under conditions of a sudden increase of temperature on the outside of the casing, that the expansion of the body of air in chamber 1 will act to raise the liquid column.

By the provision of the well 2^a in the bottom of the casing 2, a contracted space is formed at the lower end of the tube into which the liquid must enter before it can rise in the tube. Hence when the level in the chamber is reduced by the rise of the liquid in the tube, there will be no liability of an interruption being formed between the liquid in the column and that remaining in the chamber.

In the attachment of the apparatus to the ceiling for instance, I propose to employ a block 11 which is adapted to be fastened in place by suitable means. This block contains a central opening 11^a through which the conductors from the terminals pass to the line. Secured to the lower face of the block is a plate 12 provided at opposite sides with oppositely extending keyhole slots 13 adapted to receive headed pins 14 projecting upwardly from the plate 3. In fastening the casing in position, the latter is applied to the under side of the block and the pins 14 entered in the ends of the keyhole slots, whereupon the casing is given a slight circumferential movement so as to interlock the heads of the pins with the edges of the slots.

In the modified form of the apparatus shown in Fig. 2, the construction is the same as that just described except in respect to the float 7, which in this case is in the form of a cup 7^a containing a conductive body 7^b preferably of mercury. The ends of the terminals are extended downwardly vertically as at 8^a and 9^a in such position that while under normal conditions the level of the mercury will be below and out of contact with the terminals, yet when the cup is

raised by the rise of the liquid column, the mercury body will be carried into engagement with the terminals and will form an electric connection between them and thus close the circuit.

The conductors of the electric circuit are shown in the present case as connected with a device A, which may be an alarm bell adapted on the closure of the circuit in the manner set forth to be sounded to give an alarm. It will be understood however, that the apparatus is not limited in its application to a signaling device of this type, as the electric conductors may be connected up to operate other devices, such as sprinkler systems, and to perform other functions, the invention residing in the construction of the circuit controller itself, without regard to the detailed construction of the apparatus operated by the circuit.

By forming the vent opening 10 in the plate 3, said opening is housed by the plate 12 and block 11 from direct communication with the space exterior of the casing 2, although the fit of the casing 2 against the block is not sufficiently tight to prevent the escape of the air from the expansion chamber to the outside. As a result, the vent opening, which is of a very restricted character to perform its functions, is protected against the entrance of dust or dirt from the space in the room, and the liability of the opening becoming clogged up by foreign matters, is reduced to a minimum.

In the foregoing description and in the accompanying drawings I have shown my invention embodied in the particular form and detailed construction which I prefer to adopt, but it will be manifest to the skilled mechanic that these details may be variously changed and modified without departing from the limits of the invention; and it will be understood that the invention is not limited to any particular form or construction of the parts except in so far as such limitations are specified in the claims.

Having thus described my invention, what I claim is:

1. In a thermostatic controller, the combination of a hollow open casing, a plate fitting over the end of the same and constituting in connection therewith a fluid expansion chamber, a liquid column in said chamber adapted to be raised by the expansive action of the fluid therein and acting when raised to control an electric circuit, a supporting block provided with slots, and pins on the plate adapted to enter the slots and effect a detachable connection of the casing with the block.

2. In a thermostatic controller, the combination of a hollow open casing, a plate fitted in the open end of the casing and constituting in connection therewith a fluid expansion chamber, a liquid column in said

chamber adapted to be raised by the expansive action of the fluid, an electric circuit adapted to be controlled by the rise of the liquid column, and a supporting block to the face of which the plate and connected casing are detachably connected, the said plate being provided with a restricted vent opening; whereby the said vent opening will

be protected by the block from the direct entrance of dust or dirt therein.

In testimony whereof I have affixed my signature in presence of two witnesses.

BRUCE V. EDWARDS.
